ASSIGNOR TO ROBERT S. HUMPHREY, OF COUNCIL BLUFFS, IOWA.

PASTEURIZING-MACHINE.

986,237.

Specification of Letters Patent. Patented Mar. 7, 1911.

Application filed June 21, 1910. Serial No. 568,203.

To all whom it may concern:

Be it known that we, EDWARD J. SPINK and JOSEPH A. MILLER, citizens of the United States, residing at Council Bluffs, in 5 the county of Pottawattamie and State of Iowa, have invented a new and useful Pasteurizing-Machine, of which the following is a specification.

Our invention relates to improvements in 10 pasteurizing machines, and has for its object the provision of a simple and efficient apparatus by the use of which liquids may be easily, thoroughly, and rapidly pasteurized so as to be rendered healthful without 15 losing any of their palatable qualities.

A further object of the invention is to provide an apparatus in which scalding of the liquid will be avoided and in which the flow of the liquid will be automatically regulated so that the entire body will be treated 20 without interruption.

A further object of the invention is to provide an apparatus for the stated purpose which will be simple in construction, compact in arrangement, and efficient in operation.

These stated objects, and such other objects as will hereinafter incidentally appear, are attained in the use of the mechanism 30 illustrated in the accompanying drawings, and the invention consists in certain novel features of the same which will be herein-after first fully described and then more particularly pointed out in the appended claims.

In the drawings,—Figure 1 is a diametrical vertical section of an apparatus embodying our invention. Fig. 2 is a plan view, partly broken away, of the pasteurizing disks and the parts below the same. Fig. 3 is a detail plan view of the mechanism whereby the flow of the liquid is regulated. Fig. 4 is a sectional elevation of a modification.

In carrying out our invention, we employ 40 a supporting structure consisting of legs or standards 1 and a circular band 2 secured to the upper ends of the said legs, the legs being each provided with inwardly projecting arms 3 having notched upper edges, as clearly shown in Fig. 1.

To the upper edge of the ring or band 2, we secure a pair of slightly conical disks 4 and 5 which are spaced apart to provide 50 a compartment 6 adapted to contain water,

steam, or other agent, the edges of the two disks being secured together at the edge of the supporting band. The surface of the upper disk is formed into corrugations 8 which radiate from the center of the disk 60 and are curved so as to retard the flow of the liquid over the disk, while at the same time directing it outward toward the trough 9, formed around the edge of the disk, which leads into a discharge spout 10 at one side 65 through which the liquid may escape into any convenient receptacle. These corrugations 8 are curved, as shown most clearly in Fig. 2, so that their outer ends will be somewhat wider than their inner ends and the 70 liquid will be retarded in its flow to the edge of the disk and spread out somewhat as it reaches the edge so that the entire body of liquid may be treated, and this flow will be retarded sufficiently to prevent any portion 75 escaping treatment, while at the same time it will be sufficiently rapid to prevent scalding of the liquid.

The lower disk 4 is smooth and is provided, at its center, with a depending nipple 80 11 in which is fitted a small pipe 12, leading from a coupling 13, from which pipes 14 radiate to points below the trough 9 of the upper disk where they communicate with short pipes 15 leading into an annular depression, 16 around the edge of the lower disk. One of these pipes 14 is connected at its outer end with a valve 17 through which the device may be drained of the water, steam or other agent, when it is not in use 90 and cleaning of the same is desired. The compartment 6 between the two disks, as well as the pipes 12 and 15 leading therefrom, are supplied with water or steam or other agent through a feeding pipe 18 which 95 extends centrally upward from the upper disk 5 and communicates, at its upper end, through a branch pipe 19 with an expansion tank 20. The upper end of the feeding pipe 18 is closed by a plug 21, and a funnel-shaped cap or pan 22 is secured upon the said upper end, as clearly shown in Fig. 1. The water is brought into the feeding pipe 18 after the plug 21 is removed and the branch pipe 19 and the tank 20 will accommodate the expansion of the same when heat 105 is applied to the lower disk in the operation of the apparatus.

Supported upon the feeding pipe 18 is a distributing tank 23 provided with a series 110

of perforations 24 in its bottom, around its outer edge, through which the milk, or other liquid to be sterilized, will escape in fine streams onto the upper pasteurizing conical disk. This regulating or distributing tank 23 is provided with a lateral spout 25, through which the milk or other liquid flows to enter the tank, and this spout receives the liquid through a nozzle 26 leading from the reservoir or hopper 27 which, when the device is in use, will rest upon the pan 22, as shown in Fig. 1. A float 28 is arranged within the distributing tank 23 and is secured to the end of a lever 29 disposed longitudinally within the spout 25, as shown clearly in Figs. 1 and 3, the said lever being pivoted, at 30, to a collar or clamp 31 secured around the lower end of the nozzle 26. On the upper side of the lever immediately below the nozzle is a tapered plug or valve 32 which is adapted to enter the lower end of the nozzle and cut off the flow therethrough, as will be readily understood. The supply of liquid to be treated is placed in the hopper 27 and will flow therefrom through the outlet tube 33 into the nozzle 26 and then into and through the spout 25 to the tank 23, a plug valve 33^a being provided within the nozzle to cut off the flow when so desired. From this tank, it will pass in a plurality of very fine streams onto the upper pasteurizing disk 5 over which it will flow, as before described. In order to prevent flooding of the distributing tank 23 or the pasteurizing disk, the float 28 and the valve 32 will automatically control the flow from the nozzle 26. As the liquid collects in the tank 23, the float will rise and thereby carry the lever 29 upward so that the plug or valve 32 will be inserted into the lower end of the nozzle and thereby cut off or diminish the flow therefrom. Should the liquid be escaping from the tank faster than it flows into the same, the float will fall and the valve thereby withdrawn from the end of the nozzle so that the liquid may flow in greater volume from the nozzle. In this manner we maintain automatically the desired flow of the liquid over the pasteurizing disk.

Seated in the notched upper edges of the lateral arms 3, is a circular burner consisting of a pipe 34 provided with a series of narrow slits 35 in its upper side and coupled to a supply pipe 36 through which gas or other fuel may be admitted to the burner. The supply of liquid or gaseous fuel having been admitted to the supply pipe 36, it will rise into and fill the burner and, escaping from the same through the slits 35, will be ignited and will, consequently, direct a practically continuous flame against the under side of the lower disk at the edge of the same. A flue 37 is arranged to carry off the products of combustion and has its

inner end disposed beneath the center of the pasteurizing disks, and has its outer end at any convenient distant point to discharge the products of combustion into the atmosphere. It will be observed that this flue 70 extends downward under the supporting band 2 so as to avoid the cutting and, consequently, weakening of the said band and does not interfere with the stability of the device in any way. The effect of this flue 75 is to create a draft from the side of the apparatus toward the center of the same so that the flame issuing from the burner will be caused to follow the under surface of the lower disk so as to heat the entire disk. 80

The construction shown in Figs. 1 and 2 and hereinbefore described is that preferred by us, but we do not limit ourselves thereto. In Fig. 4, we have illustrated the pasteurizing disks as being more pronouncedly 85 conical than those shown in Fig. 1, and the upper disk instead of being corrugated, as hereinbefore described, is constructed with a spiral groove or trough 38 which leads from the upper portion or apex of the disk down 90 to a discharge spout 39. This construction will operate in all respects the same as the construction preferred by us but is better adapted to operating on a small scale.

The operation of our device is believed to 95 be obvious from the foregoing description, taken in connection with the accompanying drawings. The liquid to be treated, as before stated, is placed in the hopper 27, the compartments 6, the feeding pipe 18, and the 100 pipes 14 and 15 having been first filled with water and the plug 21 inserted in place. The burner being lighted, the liquid in the compartment 6 will be heated so that the temperature of the upper pasteurizing disk 105 5 will be raised but will be modified by the presence of the liquid in the compartment between the two disks so that it cannot reach such a high temperature as will be liable to scald or boil the liquid to be pasteurized. 110 The milk or other liquid will then flow through the distributing tank 23 onto the pasteurizing disk and will run over the same through the corrugations therein into the trough 9 and escape therefrom through the spout 10. The flow of the liquid over the disk will be slow enough to permit all germs therein to be destroyed, while it will be rapid enough to prevent deterioration in its quality through scalding or boiling. 115

Our apparatus is so constructed as to occupy very little space compared with its efficiency in operation. The several parts coming in contact with the milk can be easily separated so as to be cleaned, as the hopper 27 with the nozzle 26 can be lifted off the pan or rest 22 and, by merely removing the coupling 40 from the feed pipe 18, the distributing tank 23 may be lifted from the said feed pipe, as will be readily 120 125 130

understood. The distributing tank 23 is provided with a central sleeve 41 adapted to fit around the water feeding pipe 18, and the bottom of the tank rests upon an annular shoulder or rib 42 on the said pipe so that it is not necessary to secure the tank to the pipe in order to prevent dropping of the same onto the pasteurizing disk. The construction of the upper disk, over which the fluid flows, provides a large surface over which it will spread so that the proper amount of heat to accomplish the desired purpose may be absorbed by the milk without destroying the natural condition of the same for cream or butter making purposes or altering its taste. The annular supporting band 2 incloses the burner and the water pipes so as to prevent the heat from the burner passing around the outer edge of the disks and thereby reaching the milk, and at the same time prevents the odors of the burning fuel impregnating the milk. Furthermore, this arrangement holds the heat below the disk so that the temperature of the liquid in the several pipes and the compartment between the two disks will be kept even while the apparatus is in use, and the arrangement of the cones is such that the proper heat will be economically maintained. A larger volume of water will absorb and consume a greater amount of heat to produce the same results and thereby increase the cost of operation, while a smaller volume of water is apt to permit the sudden generation of steam which would drive out the water and produce a fluctuating temperature. The flame, being created near the outer edge of the disks and then being drawn toward the center, produces perfect combustion and allows the fullest extraction of heat units to perform the desired work. Inasmuch as the foul gases and other products of combustion are carried off from the center of the apparatus and below the same, it is not necessary to mutilate the disks to provide an exit for the said gases and other products and, consequently, the entire surface of the upper disk may be used for the pasteurization. The disks may be pressed from a single sheet of metal leaving no seams or corners therein so that the surfaces will be smooth and easily cleaned, while at the same time there will be no part of the surface which will not be underlined with hot water or other liquid for pasteurizing. Should it be desired to use the device for cooling or refrigerating milk, it is only necessary to substitute for the hot water, cold water or a freezing agent and then permit the liquid to flow over the disks, as described, without requiring the use of the burner.

While we have described the principle of operation of the invention, together with the apparatus which we now consider to be

the best embodiment thereof, we desire to have it understood that the apparatus shown is merely illustrative, and that such changes may be made when desired as are within the scope of the claims appended hereto. 70

Having thus described our invention, what we claim is:—

1. In a pasteurizing machine, a hopper for the material to be pasteurized, a pasteurizing disk, and a distributing tank all in the same axis with the distributing tank intermediate of the hopper and pasteurizing disk, and means for conveying the material to be pasteurized from the hopper to the distributing tank in quantities determined by the amount of material in the distributing tank, said distributing tank having outlet means in surrounding relation to the common axis of the hopper, tank and disk. 75

2. In a pasteurizing machine, a hopper for the material to be pasteurized, a pasteurizing disk having means for causing the material to be pasteurized to spread thereon to a greater width than depth, a distributing tank intermediate of the hopper and disk, said hopper, tank and disk having their longitudinal axes coincident, connections between the hopper and distributing tank for conveying material to be pasteurized from the hopper to the distributing tank for deposition upon the disk, a water chamber for the side of the disk remote from that receiving the material to be pasteurized, and a heater in operative relation to substantially the entire marginal portion of the 100 water chamber. 90

3. In a pasteurizing machine, a hopper, a distributing tank, and a pasteurizing disk all in the same longitudinal axis, the distributing tank being intermediate of the hopper and disk and provided with means for the escape of the material to be pasteurized on to the disk in surrounding relation to the central axis thereof, said disk having its receiving surface provided with means for causing a flow of the material of greater width than depth thereover, connections between the hopper and distributing tank provided with controlling means responsive to variations in level of material in the distributing tank, and a heater for the disk in operative relation to substantially the entire marginal portion thereof. 110

4. In a pasteurizing apparatus, a hopper, a distributing disk, a hollow stem rising from the disk and supporting the hopper, said stem having a passage therethrough communicating with the face of the disk remote from the hopper, a fluid supply tank communicating with the hollow stem, a distributing tank carried by the stem between the hopper and disk, connections between the hopper and tank for supplying the latter with material to be pasteurized, said last named tank being provided with means for 125 130

- the outflow of material on to the disk, a chamber in underlying relation to the disk with the latter forming the corresponding wall of the chamber, said chamber being in communication with the first named tank through the hollow stem, a burner for heating the water chamber, and circulating means for the water chamber in inactive relation to the burner.
10. 5. The combination of a support, a pasteurizing disk thereon, a liquid holding compartment below the said disk, a liquid supply pipe rising centrally from the said disk, a closure for the upper end of the said pipe, 15 a branch leading laterally from the said supply pipe, and an expansion tank on the said branch.
6. The combination of a support, a pasteurizing disk thereon, a liquid compartment 20 below the said disk, a liquid supply pipe rising centrally from the said disk and communicating with the said compartment, a closure for the upper end of the said pipe, a cap secured on the upper end of the said pipe, a hopper resting on the said cap, a distributing tank fitted around and supported by the liquid supply pipe and adapted to distribute fluid onto the pasteurizing disk, and means for conveying fluid from the 30 hopper into said tank.
7. The combination of a plurality of supporting legs, a circular band secured to the said legs at the upper ends thereof, lateral arms projecting inwardly from the said legs 35 and having notched upper edges, spaced disks secured upon the upper edge of the circular band, means for circulating fluid over the upper disk, means for supplying liquid to the space between the disks, and a circular 40 burner seated in the notched arms immediately below the lower disk and following the circumference of the same.
8. In a pasteurizing machine, the combination of a support, a conical disk thereon 45 provided with a corrugated surface, the said corrugations radiating from the center of the disk toward the edge of the same and the edge of the disk being formed into a trough communicating with the outer ends of the said corrugations, means for distributing a fluid upon the disk at the center 50 of the same, and means for supplying a temperature-controlling medium to the under side of the disk.
55. 9. In a pasteurizing apparatus, a pasteurizing disk, means for directing the material to be pasteurized on to the disk, said disk being shaped to cause a flow of the material from the central portion of the disk to the periphery thereof, a water receiving chamber under the disk and of which the disk forms the upper wall, said water receiving chamber having its lower wall higher at the central portion than at the marginal portions, a burner at the marginal portions of 60
- the water chamber and extending substantially the entire length of such marginal portions, and a flue for conducting products of combustion from the apparatus having an inlet end beneath and adjacent the highest portion of the end wall of the water chamber and extending beneath the burner to the exterior of the apparatus.
10. In a pasteurizing apparatus, a dished pasteurizing disk with the central portion 75 highest when in operative position, said disk being shaped to cause a flow of the material to be pasteurized of greater lateral extent than depth, a wall in spaced relation to the face of the disk remote from that for receiving the material to be pasteurized, said wall being also dished with the central portion higher than the marginal portions when the apparatus is in operative position, and a burner in operative relation to the marginal 80 portions of the said wall.
11. In a pasteurizing apparatus, a dished pasteurizing disk with the central portion 90 highest when in operative position, said disk being shaped to cause a flow of the material to be pasteurized of greater lateral extent than depth, a wall in spaced relation to the face of the disk remote from that for receiving the material to be pasteurized, said wall being also dished with the central portion 95 higher than the marginal portions when the apparatus is in operative position, a burner in operative relation to the marginal portions of the said wall, and circulating pipes connected to the space between the said wall 100 and the pasteurizing disk and underlying the burner.
12. The combination of a hopper, a distributing tank arranged directly underneath the hopper and having a lateral spout, a nozzle leading from the hopper and arranged to discharge into said spout at the outer end thereof, a lever pivotally supported at its outer end and arranged within the spout to close the end of the nozzle, and a float on the 110 inner end of the said lever within the distributing tank.
13. In a pasteurizing machine, the combination of a support, a disk thereon provided with a corrugated surface, the said corrugations curving from the center of the disk toward the edge of the same, means for collecting fluid from the outer ends of the said corrugations, means for distributing a fluid upon the disk at the center of the same, and means for supplying a temperature-controlling medium to the under side of the disk.
14. The combination of a support, a pair of spaced disks secured on said support, a feeding pipe rising centrally from the upper 125 disk and communicating with the space between the disks to supply a temperature-controlling medium thereto, a distributing tank removably supported on the feeding pipe above the disks, a hopper removably 130

supported on said pipe above the tank, and means for conveying fluid from the hopper to the tank.

15. The combination of a support, a pair 5 of spaced disks secured on said support, a feeding pipe rising centrally from the upper disk and communicating with the space between the disks to supply a temperature-controlling medium thereto, an annular 10 shoulder on the pipe above the disks, a distributing tank resting on said shoulder and having a central sleeve encircling the pipe, a cap at the upper end of the pipe, a hopper resting on said cap, and means for conveying 15 fluid from the hopper to the tank.

16. In a pasteurizing machine, a distributing disk for the fluid to be pasteurized having fluid directing channels extending from the center outwardly, said channels 20 curving in the outward direction and progressively expanding in width.

17. In a pasteurizing machine, a pasteurizing disk provided with a plurality of conduits of greater width than depth and each 25 of a greater length than the radial distance from the starting point of a conduit to the edge of the disk, and a common duct into which all of said conduits discharge.

18. In a pasteurizing machine, a disk for 30 receiving and distributing material to be pasteurized, said disk having means for directing the material toward the edge thereof in a plurality of streams each of greater width than depth and of a greater 35 length than the radial distance from the point of commencement of the stream to the edge of the disk.

19. In a pasteurizing machine, a pasteurizing disk having a plurality of conduits for 40 the material to be pasteurized leading from the central portion of the disk toward the edge thereof and expanding in width as they recede from the central portion of the disk, each conduit being of greater length than 45 the radial distance from its point of commencement to the edge of the disk.

20. In a pasteurizing machine, a spreading disk for the material to be pasteurized provided with means for separating such 50 material into a plurality of streams and retarding the flow thereof toward the edge of the disk.

21. In a pasteurizing machine, a distributing disk for the material to be pasteurized, 55 said disk having an approximately conical form with channels in its surface widening from the central portion of the disk toward the edge thereof and each also curving in the direction of its length, and a trough 60 formed in the outer edge of the disk and communicating with the outer ends of all the channels.

22. In a pasteurizing machine, an approximately conical disk having means for directing the material to be pasteurized from 65

the central portion of the disk to the outer portion thereof, and a distributing tank located above the central or apex portion of the disk and provided with means for distributing the material to be pasteurized at a plurality of points about the central portion of said disk.

23. In a pasteurizing machine, a distributing disk, a compartment therebelow for water, conduits connecting the central portion and the edge portions of the water compartment to constitute a circulating system, and a heater for the water compartment adjacent the latter between the same and the circulating conduits.

24. In a pasteurizing machine, a distributing disk, a compartment therebelow for water, conduits connecting the central portion and the edge portions of the water compartment to constitute a circulating system, a heater for the water compartment adjacent the latter between the same and the circulating conduits, and an expansion member above and communicating with the water compartment.

25. In a pasteurizing apparatus, a water compartment having its top formed of a disk with means thereon for directing the material to be pasteurized from the central portion toward the edge thereof, a distributing means for depositing the material to be pasteurized on said top member of the water compartment, a heating member below and in operative relation to the outer portion of the water compartment, an expansion member above and communicating with the water compartment, circulating conduits connected with the central and edge portions of the water compartment and extending below the heater, and a conduit for the products of combustion extending from a point adjacent the central portion of the undersurface of the water compartment to and beyond the edge of the water compartment beneath the latter.

26. In a pasteurizing apparatus, a dished pasteurizing disk with the central portion highest when in operative position, said disk being shaped to cause a flow of the material to be pasteurized of greater lateral extent than depth, a wall in spaced relation to the face of the disk remote from that for receiving the material to be pasteurized, said wall being also dished with the central portion higher than the marginal portions when the apparatus is in operative position, a burner in operative relation to the marginal portions of the said wall, and circulating pipes extending below the burner and connected to the space between the said wall and the pasteurizing disk both at the margin of said space and at the intermediate portion thereof.

27. In a pasteurizing apparatus, a dished pasteurizing disk with the central portion

highest when in operative position, said disk being shaped to cause a flow of the material to be pasteurized of greater lateral extent than depth, a wall in spaced relation to the face of the disk remote from that for receiving the material to be pasteurized, said wall being also dished with the central portion higher than the marginal portions when the apparatus is in operative position, a burner in operative relation to the marginal portions of the said wall, circulating pipes extending below the burner and connected to the space between the said wall and the pasteurizing disk both at the margin of said

space and at the intermediate portion thereof, and an expansion tank above and connected to the space between the said wall and pasteurizing disk through said pasteurizing disk. 15

In testimony, that we claim the foregoing 20 as our own, we have hereto affixed our signatures in the presence of two witnesses.

EDWARD J. SPINK.
